UNITED STATES PATENT OFFICE.

GEORGE HENRY WHITE, OF OIL CITY, PENNSYLVANIA, ASSIGNOR TO S. R. DRESSER MANUFACTURING COMPANY, OF BRADFORD, PENNSYLVANIA.

BLANK FOR THE MANUFACTURE OF MIDDLE RINGS FOR PIPE-COUPINGS, &c.

No. 922,990.

Specification of Letters Patent.

Patented May 25, 1909.

Application filed October 15, 1907. Serial No. 397,541.

To all whom it may concern:

Be it known that I, GEORGE HENRY WHITE, citizen of the United States, residing at Oil City, in the county of Venango 5 and State of Pennsylvania, have invented certain new and useful Improvements in Blanks for the Manufacture of Middle Rings for Pipe-Couplings, &c.; and I do hereby declare the following to be a full, clear, and 10 exact description of the invention, such as will enable others skilled in the art to which it appertains to make and use the same.

My invention consists in the novel features hereinafter described reference being 15 had to the accompanying drawing which illustrates one form in which I have contemplated embodying my invention and said invention is fully disclosed in the following description and claim.

20 The object of my invention is to provide a metal bar or blank adapted especially for the manufacture of middle rings for rubber packed pipe couplings. These middle rings are provided with a substantially central internally projecting centering stop and the end portions of the ring are provided with packing engaging portions which are usually bent or flared outwardly to form an annular packing recess at each end of the ring.

25 My present invention consists of a bar or skelp, which is formed of wrought metal as wrought iron or steel, and is preferably formed by rolling. The bar is of greater length than breadth and of greater breadth 30 than thickness, and is provided on one face with a central longitudinally disposed bead, extending throughout the length of the bar or blank, or it may be interrupted at intervals. I prefer to have the bead extend 35 throughout the length of the bar or blank. The lateral edges of the bar or blank, are preferably oppositely beveled or inclined in such a manner that the beveled edges if produced would intersect on the same side of the 40 bar on which the bead is located, or in other words the beveled edges converge toward the beaded face.

45 Referring to the drawings, Figure 1 is a perspective view of a bar, blank or skelp embodying my invention. Fig. 2 is a transverse sectional view of the same. Fig. 3 is a side elevation of a blank or bar suitable for lap-welding. Fig. 4 is an elevation of the blank or bar shown in Fig. 3 bent into ring

form preparatory to welding. Figs. 5 and 6 55 are sectional views of rings produced from my improved bar or blank. Fig. 7 is a sectional view of a modified form of bar or blank.

In Fig. 1 I have shown in perspective a 60 piece of the skelp or bar as it comes from the rolls. A represents the body of the bar; a' the longitudinal bead, and a² a² the beveled lateral edges converging toward the beaded face, as clearly shown in cross section 65 in Fig. 2. When the ring is to be made by lap-welding the bar is cut in suitable lengths by incisions inclined to the faces of the bar and parallel to each other so that the blank is provided with parallel inclined end faces 70 a³ a³ as clearly shown in Fig. 3. If the rings are to be butt-welded, however, the ends of the blanks may be perpendicular to the faces as will be obvious.

75 Fig. 3 shows a complete blank suitable for lap-welding. Fig. 4 shows the blank bent into position to be welded with the bead a' on the inside. Fig. 5 is a sectional view of the ring after welding, showing the beveled ends of the ring formed by the beveled edges 80 of the blank, or bar. Fig. 6 shows in section a ring which has had its end portions flared outwardly to bring the beveled portions perpendicular to the longitudinal axis of the 85 ring.

90 Fig. 7 is a sectional view of a modified form of blank or bar indicated at A', having the central bead a', and having the lateral edges perpendicular to the broad faces, instead of beveled. The process of treating 95 this blank is disclosed in my application Serial No. 295,889, filed Jan. 13, 1906.

What I claim and desire to secure by Letters Patent is:—

95 The herein described blank for a middle ring for pipe couplings, consisting of a bar of wrought metal having a longitudinally disposed bead substantially centrally located on one face and having its lateral edges beveled oppositely and converging toward said 100 beaded face.

In testimony whereof I affix my signature, in the presence of two witnesses.

GEORGE HENRY WHITE.
